UNITED STATES PATENT OFFICE.

JOSEPH SCHULTZ, OF POTTSTOWN, PENNSYLVANIA.

DETACHABLE-CALK ATTACHMENT FOR HORSESHOES.

1,254,439.

Specification of Letters Patent.

Patented Jan. 22, 1918.

Application filed July 25, 1916. Serial No. 111,149.

To all whom it may concern:

Be it known that I, JOSEPH SCHULTZ, a citizen of the United States, residing in Pottstown, Pennsylvania, have invented certain Improvements in Detachable-Calk Attachments for Horseshoes, of which the following is a specification.

My invention relates to a detachable calk structure which can be readily applied to a horseshoe when it is desired that the horse shall be rough shod and as readily removed when the permanent calks on the shoe are considered sufficient.

In the accompanying drawing—

Figure 1 is a bottom view of a horseshoe having applied thereto a supplementary calk structure constructed in accordance with my invention;

Fig. 2 is a longitudinal section on the line 2—2, Fig. 1; and

Fig. 3 is a transverse section on the line 3—3, Fig. 1.

In Figs. 2 and 3 the shoe and the calk-carrying structure thereon are shown in their normal positions instead of being inverted as in Fig. 1.

In the drawing, 1 represents an ordinary horseshoe having the usual fixed toe calk 4 and heel calks 5. Bearing against the inner face of the front end of the shoe is a bar 6 which has upper and lower flanges 6^a bearing, respectively, upon the upper and lower sides of the said front portion of the shoe so as to retain the bar 6 in a proper vertical position in respect thereto.

At each end of the bar 6 is a depending boss 7 which bears against the under face of the shoe 1 and has secured to it in any suitable way a depending calk 8, preferably sharpened, as shown in the drawing. Extending rearwardly from the bar 6 is a plate 9 having therein longitudinal slots 10, as shown in Figs. 1 and 2, and through each of these slots passes a bolt 11 which is screwed into a bar 12 on the upper face of the plate 9, each of said bolts 11 being also in pivotal engagement with the forward end of an arm 13, whose rear end is secured to or forms part of a head 14, said head being in vertical engagement with the flat upper and lower faces of the shoe 1 and also in engagement with the inner face of the heel portion of the shoe and with the front face of the rear calk 5, as shown in Figs. 1 and 3.

Between the heads 14 is interposed a strut 55 to prevent said heads from moving inwardly toward one another, said strut being preferably composed of an externally threaded member or bolt 15 and an internally threaded member or nut 16 in threaded engagement therewith, said member 15 having a squared end engaging a square socket in one of the heads 14, and said member 16 having a rounded end engaging a round socket in the other head 14, in order that the member 16 can be turned on the member 15 when it is desired to forcibly thrust the heads 14 apart and into engagement with the inclined inner face of the heel portions of the shoe, as shown in Fig. 1. Secured to and depending from the heads 14 are calks 17, preferably sharpened in the same way as the calks 8, as shown in Figs. 2 and 3.

In applying the attachment to a horseshoe the bar 6 is first slipped into engagement 75 with the forward end of the shoe, as shown in Fig. 2, and the bolts 11 are then moved rearwardly in the slots 10 of the plate 9 until the heads 14 at the rear ends of the links 13 are jammed tightly against the rear 80 ends of the shoe and the rear calks 5, whereupon the tightening of the bolts 11 will retain the parts in this position and prevent release of the calk-carrying attachment from the shoe. When such release is desired the 85 bolts 11 are loosened and the bar 6 and heads 14 may be moved toward one another until they are free from engagement with the shoe and can be removed therefrom.

As compared with previous calk-carrying 90 attachments of which I have knowledge, my attachment possesses the advantages of fewness of parts and simplicity and cheapness of construction, and while it insures firm grip of the shoe upon a slippery roadway it 95 does not increase the weight of the shoe to an objectionable extent.

I claim:

The combination of a horseshoe with a calk-carrying attachment comprising a calk-carrying bar having bosses in vertical engagement with the front portion of the shoe and having a plate extending rearwardly therefrom and provided with longitudinal slots, heads in vertical engagement with the 100 heel portions of the shoe and having arms projecting forwardly therefrom, clamping bolts for said arms occupying said slots in

the plate, and an adjustable strut for the heads, said strut comprising a threaded bolt in non-rotative engagement with one of said heads and a nut in threaded engagement with said bolt and in revoluble engagement with the opposite head.

In testimony whereof, I have signed my

name to this specification, in the presence of two subscribing witnesses.

JOSEPH SCHULTZ.

Witnesses:

O. L. EVANS,

WILLIAM EDELMAN.
